STEEL SHELF
Rudolf Johan Koreska-Hvidegaard Birkerd Denmark

Filed Oct. 1, 1962, Ser. No. 227,391

Patent Oct. 1, 1935, Ser. No. 21,552
Filed Sept. 9, 1933
Claims. (Cl. 211—153)

editio scholastica editio nO. subtiliter eius est hoc à amicis
Theodori et Petri 1470. 1471. 1472. 1473. 1474. 1475. 1476. 1477.

The invention relates to a steel shelf that comprises:

a plate portion that is formed with a rectangular, plane main portion, and which has reinforcements along two longitudinal edges; a knife situated on this tetrahedron 61

A steel shelf is known in which the reinforcement at one of the longitudinal edges is formed from the steel plate portion itself, the latter being at the edge bent round.

plate portion itself, the latter being at the edge bent round to form a first strip-shaped portion that extends vertically downward, and in continuation of this a second

It is the object of the invention to devise a steel shelf that, with a relatively small reinforcement height along at the least one of the longitudinal edges, has a con-

The object of the invention is, furthermore, to devise a bridge for a railway or tramway which will have a considerable bearing capacity, so that it is not necessary to employ a special supporting rail.

a steel shelf of a simple and cheap construction, and that it is also the object of the invention to devise a shelf that is well suited for placing information along a long

It is further the object of the invention to devise a steel shelf in which a surface coating, e.g. varnish or a dyed or layer of plastic is hardly liable to be damaged

glued-on layer of plastic, as may be liable to be damaged at the front edge of the shelf.

The steel shelf according to the invention comprises a steel plate portion that is formed with a rectangular

plane main portion, along one of the longitudinal edges of the main portion an approximate 180° curvature that has to one side a flushing transition to the main portion, in continuation of the other side of the 180° curvature a first strip-shaped portion having flushing transition to the 180° curvature and lying approximately parallel to the main portion, and in continuation of the first strip-shaped portion a second strip-shaped portion extending approximately at right angles to the plane of the main portion and parallel to said longitudinal edge of the main portion. By these means a considerable reinforcement is obtained in a simple way with negligible height of the reinforcement members. The second strip-shaped portion may easily be arranged for placing of ribbons with information about the contents of the shelf or for placing of members on which such ribbons may be placed. The surface coating may extend beyond the 180° curvature, so that a sharp edge does not exist where the coating is liable to be damaged by bumps.

The steel portions may comprise, according to the invention, a third strip-shaped portion in continuation of the second strip-shaped portion and extending approximately parallel to the plane of the main portion in a direction toward the vertical plane, that is tangentially to the 180° curvature. By these means is obtained a further reinforcement of the shelf edge and the third strip-shaped portion may be formed for holding a ribbon with information.

According to the invention, on that side of the second strip-shaped portion that faces the vertical plane that is

2. *incorruptible*
tangential to the 180° curvature, the back portion of a U-shaped rail may be fastened the arms of which are directed away from the second strip-shaped portion and at their free edges comprise bent portions directed toward each other, in which the U-shaped rail is placed, and completely filled out by a strip of resilient material bearing elastically against the back portion of the rail and the bent portion of the arms. By these means is obtained a construction that is specially well suited for detachably placing thereon ribbons with information, said ribbons being set in and taken out while pressing the resilient strip inward.

According to the invention the steel shelf may further be provided with a portion that limits a groove, along that longitudinal edge that lies opposite the 180° curvature, the mouth of the groove lying very close to the face of the main portion and being directed toward the mouth of the groove formed by the 180° curvature, the portion of the main portion lying nearest said curvature and the groove-defining first strip-shaped portion. Therefore the shelf is well suited for applying thereto a U-formed book support projecting generally downward from the underside of the shelf, and two spring arms engaging the two grooves.

In the case where the steel shelf has a third strip formed portion, as mentioned above, the latter may extend in a direction converging with the direction of the first strip-shaped portion so that the first, the second and the third strip-shaped portions form an undercut groove. Such a groove is suited for holding fast one or more objects. Thus there may be inserted, according to the invention, into the groove a fitting part of a wood list. Such a wood list assists effectively in reinforcing the shelf and provides, in connection with the 180° curvature, an esthetically pleasing impression. The wood list may be formed for placing information on it. It may thus have a longitudinally extending list wherein portions of plastic letters can be placed so as to hold them fast.

According to the invention the steel plate portion may, at its longitudinal edge opposite the 180° curvature, have a strip-shaped portion extending approximately at right angles to the main portion in a direction opposite the 180° curvature. When setting the shelf up it is turned such a way that the 180° curvature lies downward and the said strip-shaped portion will therefore extend upward and thus form a stop so that books cannot be pushed too far toward the rear. The said strip-shaped portion reinforces furthermore the shelf edge.

According to the invention the steel shelf may comprise a steel plate portion formed with a rectangular plane main portion along one of the longitudinal edges of the main portion an approximately 180° curvature that has on one side a flushing transition to the plane portion, and in continuation of the other side of the 180° curvature a strip-shaped portion that has a flushing transition to the 180° curvature. The shelf comprises furthermore a special section rod fastened on the strip-shaped portion and extends away from the latter in a direction away from the face of the main portion. By means of this construction the steel plate may have a relatively slight thickness, while the special section rod has a greater thickness so that a specially effective reinforcement is obtained with a slight expenditure of material. At the same time the height of the reinforcement may be maintained slight.

On the steel plate portions may be glued fast a layer of plastic extending along the outer surface of the 180° curvature, along the side of the main portion flushing with said curvature and along at least a portion of the side of the strip-shaped portion facing away from the main portion. In this manner the free edge of the plastic

layer lies in a protected position in under the shelf and the freely exposed portion of the plastic layer is not exposed to damage through impact.

The invention relates furthermore to a holder for the ribbons with information. This holder is characterized in that it consists in a substantially U-formed rail, where the free ends of the arms have portions bent toward each other and where a yieldable list is placed in the rail, said list bearing yieldably to one side against the back portion of the U-formed rail and to the other side against the bent portions of the arms.

In the drawing are shown four embodiments of a steel shelf according to the invention, wherein

FIG. 1 shows a cross section of a steel shelf in a first embodiment,

FIG. 2 a cross section in the front edge portions of a steel shelf in a second embodiment,

FIG. 3 a cross section in the front edge portions of a steel shelf of a third embodiment and

FIG. 4 a cross section in both lateral sections of a steel shelf in a fourth embodiment.

In the drawings a sheet steel part comprises a rectangular, plane main portion 1 with a relatively slight thickness, e.g. 0.7 mm., along the forward edge of the main portion 1 an approximately 180° curvature 2, continued by a rearwardly extending first strip-shaped portion 3 substantially parallel to the portion 1, and in continuation of the portion 3 a second strip-shaped portion 4 extending approximately at right angles to the plane of the main portion; in connection of this portion 4 there is a forwardly directed third strip-shaped portion 5. The rear edge portion of the sheet steel part is bent upward to form a vertical supporting wall 6. On the underside of main portion 1, in the proximity of the rear edge, is fastened a U-shaped rail 7, the opening of which forms a groove directed toward the front edge of the shelf. The curved main portion 2 and the strip-shaped portion 3 together form a corresponding groove at the front edge of the shelf.

The ends of the main portion 1 may be bent downward (not shown) so that the shelf's ends can be hooked into bearing rails in a book-case.

The innermost portion of the strip-shaped portion 5 may be bent slightly upward so that the groove formed by the strip-shaped portions 3, 4 and 5 can hold a ribbon with information which can be set in from the end or, if it consists of elastic material, can be edged into place.

In the grooves at the front end and the rear edges and projecting downward under the shelf may be placed guide portions of a book-end having a downwardly projecting looped spring member which connects the guiding portions and press them yieldingly into said grooves underside the main portions.

On the front side of the strip-shaped portion 4 in the embodiment shown in FIG. 1 is fastened by spot welding a U-shaped rail with a back portion 8 and two arms 9 and 10 that are provided with edge portions 11 and 12 directed toward each other. In said U-shaped rail is placed a strip of foam rubber 13 holding a plastic ribbon 14 pressed against the edge portions 11 and 12. The plastic ribbon may carry information on its front side. By pressing it inward the ribbon may be displaced along the foam rubber strip. Several short plastic ribbons may be employed on one shelf. The foam rubber strip 13 extends preferably along the whole length of the shelf. The plastic ribbon 14 has preferably such a width that when pressing at the top or the bottom it can be pulled out at the opposite edge. Insertion may be performed in the same manner.

On the upper side of the main portion 1 there is glued a flexible plastic material 15 which at its one edge abuts the upwardly extending portion 6 while said material at the opposite edge is bent around the curvature 2 and under the strip portion 3 onto which it is also glued.

In the embodiment shown in FIG. 2 the portions 3 and 5 are inclined so that they provide an undercut groove. In this groove there is inserted a wooden list 16 in the front side of which there is formed a groove 17 for inserting rearwardly projecting fixing means of plastic letters. The wooden list may be replaced by a plastic strip having information thereon.

In the embodiment shown in FIG. 3 the strip-shaped portions 4 and 5 are omitted. On the underside of the main portion 1 there is secured, for instance by spot welding, a horizontal strip-shaped portion 18 of a steel sheet profile rod which is formed with a 180° curvature 19, a horizontal arm 20 bearing against the upper side of the portion 3, a vertically downwardly extending strip-shaped portion 21 and a forwardly extending, bent edge portion or strip-shaped portion 22. The profile rod is substantially heavier than the steel sheet from which the main portion 1 is made.

The steel shelf shown in FIG. 4 consists of a steel sheet part formed with a rectangular, plane main portion 23, at each longitudinal edge of said main portion with an approximately 180° curvature 24 and 25 respectively, and in continuation of this curvature a profile portion with generally C-profile comprising a back portion 26 and 27 an upper curved arm 28 and 29, and a lower curved arm 30 and 31, respectively. The outer portions of the arms converge greatly. In the undercut groove formed by the profile portions 27, 29, 31 there is arranged a list 32 consisting of foam nylon and shaped to fill the groove elastically so that it presses against the back portion 27 and against the converging outer end portions of the arms 29 and 31.

A strip 33 of sheet material, preferably an elastic material, is inserted in the groove in front of the list 32 so that the latter keeps the longitudinal edges of the strip 33 pressed against the converging end portion of the arms 29 and 31 so as to retain the strip 33 in position.

Pressing inward on the strip 33 results in loosening the latter so that it is easily displaced in the longitudinal direction of the groove. If the strip 33 consists of elastic material it will be easily inserted into the groove and removed therefrom without displacing it longitudinally.

I claim:

1. A steel shelf comprising, in combination, a planar sheet member formed with a rectangular, plane main portion and a curved portion along at least one longitudinal edge thereof and extending throughout an arc of at least approximately 180 degrees, said curved portion having at one side a flushing transition to said main portion, a first strip-shaped portion in continuation of the other side of said curved portion and having a flushing transition to said curved portion and being substantially parallel to the plane of said main portion, and a second strip-shaped portion in continuation of said first strip-shaped portion extending generally away from and approximately at right angles to the plane of said main portion and parallel to said one longitudinal edge.

2. A shelf according to claim 1, further comprising a third strip-shaped portion in continuation of said second strip-shaped portion and extending approximately parallel to said plane toward a substantially vertical plane tangent to said curved portion.

3. A shelf according to claim 1, further comprising a third strip-shaped portion in continuation of said second strip-shaped portion and projecting against a substantially vertical plane tangent to said curved portion in a direction converging with respect to that of said first strip-shaped portion, so that said first, said second and said third strip-shaped portions define therebetween an undercut recess.

4. A shelf according to claim 3, further comprising a wooden list inserted in said undercut recess.

5. A shelf according to claim 1, further comprising a rail portion opposite said curved portion and defining a recess having its opening adjacent said one edge and be-

ing directed toward the mouth of the recess formed by said curved portion, said rail portion being adjacent said curved and said first strip-shaped portions.

6. A steel shelf comprising, in combination, a planar sheet member formed with a rectangular, plane main portion and a curved portion along at least one longitudinal edge thereof at approximately 180 degrees, said curved portion having at one side a flushing transition to said main portion, and a profiled portion in continuation of the other side of said curved portion, having generally a C-shaped section, and including a back portion extending substantially at right angles to the plane of said main portion, and two arm portions converging toward a substantially vertical plane tangent to said curved portion.

7. A steel shelf according to claim 6, further comprising a resilient list member positioned within said profiled portion and substantially filling up the recess formed therein, said list member bearing elastically against said back portion and against the inner sides of said arm portions.

8. A steel shelf according to claim 7, wherein said profiled portion and said list member constitute marker holder means for strip-shaped markers insertable therein, said arm portions defining therebetween an undercut recess, the substantially plane front side of said list member

5

having its edges bearing against said inner sides of the arm portions for securing said markers in said holder means.

9. A steel shelf according to claim 8, wherein said list member is made from a foamed plastic material resiliently urging said markers against said arm portions.
